UNITED STATES PATENT OFFICE

157,763

HANGER FOR VACUUM CLEANERS OR
THE LIKE

John J. Kowalewski, Bronx, N. Y., assignor to Electrolux Corporation, Old Greenwich, Conn., a corporation of Delaware

Application December 3, 1947, Serial No. 142,944

Term of patent 14 years

(Cl. D9—2)

To all whom it may concern:

Be it known, that I, John J. Kowalewski, a citizen of the United States of America, residing in Bronx, New York, have invented a new, original, and ornamental Design for Hanger for Vacuum Cleaners or the like, of which the following is a specification, reference being had to the accompanying drawing, forming part thereof:

The single figure is a perspective view of a hanger for vacuum cleaners or the like showing my new design.

I claim:

The ornamental design for a hanger for a vacuum cleaner or the like, as shown.

JOHN J. KOWALEWSKI.
